UNITED STATES PATENT OFFICE.

FELIX TRAMBLAY, OF CHICAGO, ILLINOIS.

HOLDING-CLIP FOR BOX-FILES.

SPECIFICATION forming part of Letters Patent No. 545,556, dated September 3, 1895.

Application filed August 18, 1894. Serial No. 520,710. (No model.)

To all whom it may concern:

Be it known that I, FELIX TRAMBLAY, of Chicago, in the county of Cook and State of Illinois, have invented certain new and useful Improvements in Holding-Clips for Box-Files; and I do hereby declare that the following is a full, clear, and exact description thereof, reference being had to the accompanying drawings, and to the letters of reference marked thereon, which form a part of this specification.

This invention relates to improvements in file cases or boxes for use in filing letters, bills, &c., of that class wherein the papers are filed between indexed leaves held within the box or case by means of a suitable holding device in the form of a straight strip or bar engaging the index-leaves, and with which the latter have sliding engagement.

The invention relates more specifically to improvements in the construction of the said holding strip or bar, by which the index-sheets are held within the filing box or case, whereby the cost of manufacture is reduced and at the same time an article produced having superior features of utility and convenience. The holding strip or bar herein shown is particularly designed for use in box-binders, or those in which the indexed leaves having been once properly assembled upon the device, inserted in place in the box, and the latter filed with documents, the binder is in this condition filed away to be used only for future reference, as contradistinguished from temporary binders, or those in which the entire contents of the box, including the holding device and index-leaves, are from time to time removed from the binder and placed in a permanent file or cabinet, a new set of index-leaves and holding-clips being substituted for the set thus removed. As will appear from the description, however, the holding device is not permanently secured in place, and may, therefore, if necessary, be removed; but, as before stated, is especially designed for use in a permanent file.

The object of the invention is to provide an improved construction in devices of the character referred to; and the invention consists in the matters hereinafter described, and more particularly pointed out in the appended claims.

The invention will be more readily understood by reference to the accompanying drawings, in which—

Figure 1 is a view in central vertical section of a file-case embodying my invention. Fig. 2 is a perspective view of the holding rod or bar of the same. Fig. 3 is a transverse vertical section of the central portion only of the case, taken on line 3-3 of Fig. 1 and looking in the direction indicated by the arrows, the index-sheets having been removed. Fig. 4 is a horizontal section of the parts shown in Fig. 3, taken on line 4-4 of Fig. 1 and looking downward. Fig. 5 is a detail of a section of one of the index-sheets and attached clip, by which it is secured to the holding-rod.

It will be understood that my improved clip may be used in connection with various file-cases, that herein shown being, so far as general features are concerned, of the usual well-known construction.

As shown in said drawings, A designates the file-case as a whole, of which are shown the top strip or ledge A', the back A², bottom A³, front wall A⁴, and one of the end walls A⁵ of the box proper and the top B, front wall B', and end wall B² of the lid or cover. The front wall of the box A⁴ is hinged at its lower margin, so as to drop or fold outwardly, and the top B of the cover is hinged to the edge of the top strip or ledge A' at b, a short distance from the rear edge of the box, said strip A' thereby not only forming a means for connecting the lid with the box, but constituting a ledge to hold the rear edge of the index-sheets and papers within the case from rising above the top edges of the same, as heretofore common in similar file-cases.

The rear wall or back A' is provided centrally in its inner surface with a vertically-arranged recess, extending from top to bottom, for the reception of a flat and relatively thin holding bar or strip C, by which the index-sheets are held in the file-case and with which said sheets have sliding connection.

The bar C is of peculiar construction, the same being resilient in character and comprising a straight body portion c, formed of elastic sheet or plate metal of uniform width throughout its length, and provided at its ends with oppositely-extending right-angled portions c' c'. The portions c' are each pro-

vided with a plurality (in this instance two) of sharp points or teeth c^2 c^2 , formed integrally with the edge of the plate and turned so as to extend outwardly in planes substantially parallel with the main body c of the clip. The size and resiliency of the strip C will be such as to permit of its being readily bowed or sprung flatwise beneath the fingers, but yet of such stiffness as to resist considerable pressure brought endwise or upon the chair portions thereof. The holding bar or strip thus constructed is designed to be placed in position within the recess a by first placing its lower end in proper position against the bottom of the box and then bending or springing the strip flatwise, so as to shorten the distance between its ends and thrusting its upward end backwardly beneath the top strip or ledge A' . Upon releasing the strip its resiliency will cause it to resume its normal shape and thus force the upper prongs into the under face of the said ledge A' . It is to be noted that the facility with which the clip may be placed in position in assembling the binder, and the ease and certainty with which it may be properly adjusted by inexperienced or unskilled help, is a feature of much importance. By reason of the relatively wide base formed by the bent portion c' , the device having been properly adjusted at one end will assume a perfectly perpendicular position with relation to the top and bottom walls without any care on the part of the operator, thus insuring that the index-leaves will move freely thereon, whereas, in the case of prior constructions either special sockets for the ends must be provided or great care must be exercised in placing them in position. In other words, skilled help must be employed.

As hereinbefore stated, it is the intention that when the strip has once been placed in position it will not ordinarily be removed until the box is dismembered; but if for any reason it should become necessary the removal of the strip from the file-case will be accomplished by simply grasping the body of the strip and springing or curving it, when the prongs will be withdrawn from engagement and it and its connected sheets may be lifted out of the file. It is to be noted that the said strip A' may be lifted or sprung upwardly somewhat to facilitate the insertion of the upper end of the strip beneath it and into contact with the back A^2 . The angled portions c' of the bar serve to limit the penetration of the teeth into the sides of the case and also form shoulders or supports to resist external pressure on the sides of the case. The making of the bar with the angled portions $c' c'$ turned in opposite directions makes the central part of the bar stiffer as a whole and capable of better resisting end pressure than would be the case were both ends turned in the same direction and at the same time facilitates its insertion or removal.

The index-sheets D , for use in connection

with my improved clip, will each be provided with a suitable tag d , having an elongated slot adapted to fit closely upon the bar C , and thereby hold the sheets accurately in register. It is to be noted in this connection that the bar C will be so positioned within the recess a that its front face will be exactly flush with or in the same plane with the inner face of the back A^2 , so that documents inserted between the index-leaves cannot be torn, crumpled, or otherwise injured by contact with a projecting clip or uneven surface at the back of the binder.

It will be obvious from the above description that a clip constructed as described may be manufactured at a minimum cost, because its form is such that it may be stamped out by two simple operations—one to cut out the blank and one to bend or form it. As hereinbefore stated, the assembling of the clip within the file may also be accomplished at a minimum cost, and no amount of rough usage of the file will cause the points of the clip to work through the sides of the binder.

I claim as my invention—

1. A holding device for file case index sheets, comprising a straight, resilient, sheet metal strip, the end portions of which are bent at right angles to the body of the strip and are provided with teeth which project outward in planes substantially parallel with the body of the strip, substantially as described.

2. A holding device for file case index sheets, comprising a straight, resilient, sheet metal strip, the end portions of which are bent at right angles to the body of the strip and extend from opposite sides of the same, said end portions being provided with teeth which project outward in planes substantially parallel with the body of the strip, substantially as described.

3. A holding device for file case index sheets, comprising a straight, resilient, relatively wide, sheet metal strip or strap, the end portions of which are bent at right angles to the body of the strip and are provided with teeth which project in opposite directions in planes substantially parallel with the body of the strip, substantially as set forth.

4. The combination, with a file case having a bottom wall and a top wall which forms an overhanging ledge, and a series of index sheets, of a holding device for the index sheets comprising a straight, resilient, sheet metal strip, the end portions of which are bent at right angles to the body of the strip and which are provided with teeth adapted to engage the opposing surfaces of said bottom and top walls of the case, substantially as described.

5. The combination, with a file case having a bottom wall, and a top wall which forms an overhanging ledge, a series of index sheets within the case, each provided with a tag or projection at its margin provided with an elongated slot therein, of a holding device for the index sheets, comprising a straight, resili-

545,556

ent, relatively wide sheet metal strip, the end portions of which are bent at right angles with the body portion of the strip and provided at their end margins at the corners thereof with teeth adapted to engage the opposing surfaces of said bottom and top walls of the case, substantially as described.

In testimony that I claim the foregoing as my invention I affix my signature in presence of two witnesses.

FELIX TRAMBLAY.
